GAS TIGHT TANK

Application filed August 27, 1931. Serial No. 559,714.

This invention relates to gas-tight tanks and the object of this invention is to provide a tank of this character which will withstand very high internal pressure and which will be built to hold any desired volume of gas under high pressure.

We attain our object by providing a chamber having its bottom, top and sides formed of non-corrosive thin sheet steel, the sheets of which may be readily welded together to form a gas-tight chamber. This chamber is fortified on its outer side by reinforced concrete of sufficient thickness and strength to safety without very high pressure within the chamber. Cavities between the walls of the chamber and the reinforced concrete are prevented by providing the walls with suitable anchors which will be embedded in the concrete.

20 The constructions are hereinafter more fully described and are illustrated in the accompanying drawing in which

Fig. 1 is a vertical section, partly broken away, of our tank;

25 Fig. 2 a cross section on the line 2—2 in Fig. 1;

Fig. 3 a cross sectional detail on the line 3—3; and

30 Fig. 4 a cross sectional detail on the line 4—4.

In the drawing like numerals of reference indicate corresponding parts in the different figures.

The tank comprises a gas-tight chamber 35 1 having a bottom 2, top 3 and sides 4 formed of thin sheet steel. The sheets forming the sides 4 are welded together and to the bottom 2 and top 3 to form a gas-tight chamber.

To enable this chamber to withstand very 40 high internal pressure we fortify it by enclosing it in a casing 5 of reinforced concrete of sufficient thickness and strength. The outer surfaces of the walls of the sides 4, bottom 2 and top 3 of the chamber thus provide the form for the inner surface of the concrete casing 5 and, to prevent any cavities from being formed between the said metal and concrete surfaces, the metal walls are provided with laterally extending anchors 6. 45 These anchors will be welded to the outer sur-

faces of the chamber walls and may be of any suitable shape so that they will be embedded in the concrete while the latter is being poured.

The strength of the tank may be greatly increased by making the chamber 1 annular in cross section and filling in the central space with reinforced concrete 5^a. This concrete 5^a forms a column joining the upper and lower masses of concrete at the opposite ends of the tank. Anchors 6^a hold the concrete 5^a against the adjacent sides 4 of the chamber 1.

Referring to Figs. 1, 2 and 3 it will be noted that groups of reinforcing rods 7 extend vertically through the concrete walls and column 5^a beyond the top and bottom of the chamber 1. A group 8 of rods arranged horizontally adjacent each end of the casing 5 serves to anchor some of the rods 7. The upper and lower ends of the rods 7 are interlaced with rods 9 which are bowed outwardly intermediate their ends and are diametrically arranged across the ends of the casing 5. Adjacent the walls 4 of the chamber 1, the rods 7 are interlaced with rods 10 formed as hoops.

Preferably the sheets forming the bottom 2, top 3 and sides 4 are made of non-corrosive material. The sheets may be secured together by means of angle irons riveted to the marginal edges of the sheets and drawn towards one another by bolts passed through the laterally extending flanges of the angle irons. The joints are tightly welded on the inside smooth surfaces of the sheets and the laterally extending flanges of the angles are subsequently embedded in the concrete.

By building the tank as described, the steel chamber 1 prevents any gas from escaping through the concrete and its thickness is minimized to an extent that it may be readily welded.

A suitable inlet 11 and an outlet header 12 are provided for admitting and discharging gas or liquid into and out of the chamber 1. If the pressure of the fluid in the tank be sufficiently high the tank not only serves as a storage container but also as a pump adapted to transport the fluid therefrom under a high pressure for a great dis-

tance. The tank is thus adapted for use in storing and transporting liquids, particularly crude or refined oil in which case gas is first admitted to the tank and is then compressed to a very high pressure by forcing the oil therein under a high pressure. The cushion of gas at the top of the tank would serve to force the liquid from the tank at the required pressure to ensure its transportation through discharge pipes of any desired length.

Any well known means may be utilized to maintain a constant temperature within the tank.

15 What we claim as our invention is:

1. A container for fluids under high pressure, comprising a closed hollow metal cylinder having a wall thickness sufficient to ensure fluid-tightness; an enclosing network of metal adapted to resist outwardly directed stresses normal to the surfaces of the metal cylinder and as a whole providing at any point resistance to bursting stresses many times greater than that of the metal cylinder; 20 and a mass of concrete filling the spaces between the parts of the network and between the network and the exterior wall of the cylinder and serving to position the aforesaid network, the said network of metal comprising a plurality of series of metal rings spaced from one another both longitudinally and transversely relative to the axis of the container and a plurality of rods passing between the rings longitudinally of the wall and 25 extending into the ends of the container.

2. A container for fluids under high pressure, comprising a closed hollow metal cylinder having a wall thickness sufficient to ensure fluid-tightness; an enclosing network of metal adapted to resist outwardly directed stresses normal to the surfaces of the metal cylinder and as a whole providing at any point resistance to bursting stresses many times greater than that of the metal cylinder; 40 and a mass of concrete filling the spaces between the parts of the network and between the network and the exterior wall of the cylinder and serving to position the aforesaid network, the said network of metal comprising a plurality of series of metal rings spaced from one another both longitudinally and transversely relative to the axis of the container and a plurality of rods passing between the rings longitudinally of the wall and 45 extending into the ends of the container.

50 3. A container for fluids under high pressure, comprising a closed hollow metal cylinder having a wall thickness sufficient to ensure fluid-tightness; an enclosing network of metal adapted to resist outwardly directed stresses normal to the surfaces of the metal cylinder and as a whole providing at any point resistance to bursting stresses many times greater than that of the metal cylinder; 55 and a mass of concrete filling the spaces between the parts of the network and between the network and the exterior wall of the cylinder and serving to position the aforesaid network, the said network of metal comprising a plurality of series of metal rings spaced from one another both longitudinally and transversely relative to the axis of the container and a plurality of rods passing between the rings longitudinally of the wall and 60 extending into the ends of the container, certain of the rods extending substantially radially in the ends.

65 3. A container for fluids under high pressure, comprising a closed hollow metal cylinder having a wall thickness sufficient to ensure fluid-tightness; an enclosing network of metal adapted to resist outwardly directed stresses normal to the surfaces of the metal cylinder and as a whole providing at any point resistance to bursting stresses many times greater than that of the metal cylinder; 70 and a mass of concrete filling the spaces between the parts of the network and between the network and the exterior wall of the cylinder and serving to position the aforesaid network, the said network of metal comprising a plurality of series of metal rings spaced from one another both transversely and longitudinally relative to the axis of the cylinder, and a plurality of longitudinally extending rods passing between the rings.

75 4. A container for fluids under high pressure, comprising a closed hollow metal cylinder having a wall thickness sufficient to ensure fluid-tightness; an enclosing network of metal adapted to resist outwardly directed stresses normal to the surfaces of the metal cylinder and as a whole providing at any point resistance to bursting stresses many times greater than that of the metal cylinder; 80 and a mass of concrete filling the spaces between the parts of the network and between the network and the exterior wall of the cylinder and serving to position the aforesaid network, the said network of metal comprising a plurality of series of metal rings spaced from one another both transversely and longitudinally relative to the axis of the cylinder, and a plurality of longitudinally extending rods passing between the rings.

85 4. A container for fluids under high pressure, comprising a closed hollow metal cylinder having a wall thickness sufficient to ensure fluid-tightness; an enclosing network of metal adapted to resist outwardly directed stresses normal to the surfaces of the metal cylinder and as a whole providing at any point resistance to bursting stresses many times greater than that of the metal cylinder; 90 and a mass of concrete filling the spaces between the parts of the network and between the network and the exterior wall of the cylinder and serving to position the aforesaid network, the said network of metal comprising a plurality of series of metal rings spaced from one another both transversely and longitudinally relative to the axis of the cylinder, and a plurality of longitudinally extending rods passing between the rings and in which the network about the ends of the cylinder includes a plurality of bowed rods extending from the wall into the ends.

CERTIFICATE OF CORRECTION.

Patent No. 1,909,502.

May 16, 1933.

HENRY REINECKE, ET AL.

It is hereby certified that error appears in the printed specification of the above numbered patent requiring correction as follows: Page 1, line 14, for "safety without" read "safely withstand"; and that the said Letters Patent should be read with this correction therein that the same may conform to the record of the case in the Patent Office.

Signed and sealed this 8th day of August, A. D. 1933.

M. J. Moore.

Acting Commissioner of Patents.
